[57] CLAIM

The design for a combined electrical iron and base, as shown and described.

DESCRIPTION

FIG. 1 is a top plan view of the base for the combined electric iron and base according to the present invention; FIG. 2 is a bottom plan view of thereof; FIG. 3 is a left side elevational view thereof; FIG. 4 is a right side elevational view thereof; FIG. 5 is a rear elevational view thereof; FIG. 6 is a front elevational view thereof; FIG. 7 is a right side perspective view thereof; FIG. 8 is a top plan view of the electric iron for the combined electric iron and base according to the present invention; FIG. 9 is a bottom plan view thereof; FIG. 10 is a front elevational view thereof; FIG. 11 is a rear elevational view thereof; FIG. 12 is a right side elevational view thereof; FIG. 13 is a left side elevational view thereof; and, FIG. 14 is a perspective view of a combined electric iron and base showing my new design.

The iron is not shown in FIGS. 1 through 7 and the base is not shown in FIGS. 8 through 13 for convenience of illustration.
